SERVO-VALVE

Stanley H. Holmes, Chicago, Ill.

Application May 25, 1955, Serial No. 510,969

5 Claims. (Cl. 137—622)

2

vide a new and improved device of the class described with a new and improved actuator operable to actuate the mechanism by either longitudinal forces applied thereto or transverse forces applied thereto.

5 Still another object of the present invention is to provide a new and improved servo valve of the class described with an actuating plate pivotally coupled to the piston in the valve, pivotally coupled to an actuator and pivotally coupled to by-pass control means such as a

10 micro-switch of the like.

Still another object of the present invention is to provide a new and improved actuator mechanism for a servo valve of the class described.

Still other objects, features and advantages of the present invention will become readily apparent from the following detailed description of the present invention and an embodiment thereof, from the claims, and from the accompanying drawings in which each and every detail shown is fully and completely disclosed of this part of 15 the specification, in which like reference numerals refer to like parts, and in which:

Figure 1 is a more or less diagrammatic plan view of the lathe having a tool block actuator and hydraulic control system therefor embodying the principles of the present invention:

Figure 2 is an end view of a servo valve for the control system and embodying the principles of this invention; and

Figure 3 is a sectional view of the servo valve of 20 Figure 2 viewed as taken substantially along the line III—III of Figure 2.

As shown in the drawings:

There is illustrated in Figure 1 more or less diagrammatically, a fragmental portion of a lathe bed 10 carrying a live center mechanism 11 and a dead center mechanism 12 between which there is disposed a tool block 13 operable to traverse the work piece 14 held between a live center point 15 and a dead center point 16. The tool block carries a cutting tool 17 whereby the work piece 14 25 may be lathe cut to a desired contour as the tool block 13 traverses the work piece by riding on the bed 10. In addition, the tool block 13 is movable transversely of the lathe bed 10 whereby contoured configurations may be cut into the work piece 14.

40 For transverse movement of the tool block 13 with respect to the bed 10, the tool block base 18 which carries the tool block 13 and rides on the lathe bed 10 is equipped with a double acting piston and cylinder assembly 19 having a piston 20 reciprocably disposed in a cylinder 21

45 and connected to a piston rod 22 which is in turn connected to the tool block 13 whereby bidirectional operation of the piston and cylinder assembly is transmitted to the tool block 13. The piston and cylinder assembly 19 is connected from its opposite ends through fluid feed tubes 23 and 24 to a servo valve mechanism 25

50 which is provided with a feed tube 26 leading to fluid pump connected to an appropriate reservoir, the valve 25 also being provided with reservoir return tubes 27 and 28.

55 In operation, the valve 25 is equipped with a template follower stylus 29 which follows a template 30 to actuate the valve and thereby control the flow of fluid from the inlet tube 26 to the actuating piston and cylinder assembly 19 through the tubes 23 and 24 and to control return to the reservoir through the tubes 27 and 28. Thus, when the valve is moved by the movement of the stylus as the same rides on the contoured edge of the templates, it supplies fluid to the cap end of the cylinder 21 through the feed tube 24, from the pump supply

60 inlet to the tube 26, the tube 23 from the rod end of the cylinder will accommodate return fluid flow and the valve 25 will permit the return fluid flow to pass from

The present invention relates to a servo valve and a hydraulic control system, and more particularly relates to a valve mechanism and hydraulic control system for controlling bidirectional fluid actuation of any mechanism to be so actuated.

While it will be understood, of course, that embodiments of the present invention are devices and systems of general utility, the servo valve and hydraulic system described in detail hereinbelow embodying the principles of this invention are described with reference to their utilization in a control system for operating such a mechanism as a lathe with a tracer or stylus following a template whereby the lathe is operated to cut in accordance with the contour and configuration of the edge of the template. This illustration and exemplification of an embodiment of present invention has been taken here since it is an example of installation wherein the present invention may enjoy particular utility.

Thus, it is an important object and feature of the present invention to provide a new and improved hydraulic system to control bidirectional hydraulic actuation. In the illustrated and described embodiment of this invention the hydraulic system is effective to control bidirectional actuation of a piston and cylinder assembly controlling movement of a tool block on a lathe.

Another object of the present invention is to provide a new and improved hydraulic system for controlling hydraulic actuation and to effectively follow a template.

Another object of the present invention is to provide a new and improved hydraulic system with a servo valve including means therein to actuate fluid by-pass valves.

Still another object of the present invention is to provide a new and improved servo valve for an hydraulic system, this valve being operable to control fluid flow through a plurality of outlets in the valve and from an inlet into the valve.

Still another object of the present invention is to provide a new and improved servo valve mechanism with a cylinder having regions of differing internal diameters, alternate regions having the same diameter and adjacent regions having different diameters, and a piston configured to conform to the regions of a cylinder and means to control resilient reciprocation of the piston whereby fluid flow through ports in the cylinder is controlled.

Still another object of the present invention is to provide a new and improved servo valve mechanism with apertured housing segments having varied apertures therein, alternate apertures being substantially identical and adjacent apertures being different, and a plurality of piston segments assembled together with the piston segments being dimensioned to correspond to the apertures in the housing segments, means resiliently mounting the piston for axial movement within the cylinder, means to adjust the resilient bias against the piston in one direction, and means to control axial displacement in the piston whereby fluid flow through ports in the cylinder is controlled.

Still another object of the present invention is to pro-

the tube 23 to the tube 27 to return to the reservoir. When the valve 25 is actuated in an opposite direction fluid will be supplied from the tube 26 through the tube 23 to the rod end of the cylinder and the fluid in the cap end of the cylinder will return through tube 24 and the valve 25 to the reservoir return tube 28.

From the foregoing described operating characteristics of the hydraulic system and the servo valve 25, it will be readily understood that the valve is so operable to control fluid flow to the double acting piston and cylinder assembly 19 that the tool 17 will describe a path identical to that of a contoured edge on the template 30 whereby the work piece 14 will be cut in accordance with that contour. Should the contour be so sharply configurated that the ordinary operation of the valve 25 may seem insufficient to properly actuate double acting piston and cylinder assembly 19, the valve mechanism is provided with an electrically actuatable controlling mechanism whereby by-pass valves 31 and 32 will be actuated selectively to open the hydraulic feed line 26 directly to the feed tubes 23 and 24 respectively depending upon the direction of actuation.

The valve mechanism 25 is a smoothly acting valve which is operative to meter the volume of oil flowing therethrough and is effective upon actuation of the stylus to permit full flow in one direction and control velocity in the other as well as being effective to control fluid flow pressure. Additionally, the valve mechanism is adjustable for proper balancing thereof whereby the valve operation is extremely smooth.

For all of these purposes, the valve is provided with a cylinder housing 33 having an end wall 34 carrying an adjusting control mechanism 35 including an adjusting control mounting bracket 36 which is fixed to the end wall by appropriate screws 37 or the like threadably engaging the end wall 34 of the housing 33.

At the other end of the housing 33, an actuator mechanism 38 is carried on an actuator mounting bracket 39 which is secured to the housing 33 by screws 40 or the like threadably engaging the side walls of the housing 33.

The actuator end of the housing 33 is structurally open to receive a plurality of housing or cylinder segments or disks, successively identified at 41, 42, 43, 44, 45, 46 and 47, which are disposed successively in interfacial engagement with each other and held against a shoulder 48 within the housing 33 by a clamping ring 49 threadably engaging the interior of the side walls of the housing 33 at the actuator end thereof. The said disks 41-47 are axially apertured as at 41' through 47' and the clamping ring 49 is provided with an axial aperture 49'. While the dimensions of the apertures 41', 47' and 49' in the disks 41 and 47 and the ring 49 are not critical, it is important that the apertures 42', 44' and 46' in the disks or segments 42, 44 and 46 be substantially identically dimensioned and configurated, and that the apertures 43' and 45' in the disks 43 and 45 also be substantially identically dimensioned and configurated but that these latter two apertures be larger than the apertures in the rings 42, 44 and 46. Thus by this construction, alternate rings have substantially identical apertures while adjacent rings have differing apertures and the intermediate apertures be larger than the central and extremity apertures.

This dimensioning, relation and assembly of the segments or disks is important for proper operation of the valve mechanism and a proper cooperation of the cylinder portion of the valve with the piston portion thereof described immediately herein below.

Between end pairs of segments, that is, between the segments 41 and 42 and between the segments 46 and 47, there is clamped a pair of resilient thin end sealing diaphragms 50 and 51 respectively which seal in the disks 42, 43, 44, 45 and 46, and which resiliently axially carry a piston rod 52 having an enlarged actuator end

53 abutted against the outer axial interface of the diaphragm 51. A plurality of piston disks or segments 54 through 59 are then coaxially mounted on the piston rod 52 with the disks segments 55 through 59 being disposed between the resilient diaphragms 50 and 51 and the disk or segment 54 being mounted externally of the diaphragm 50 on the adjustor mechanism side thereof. The outside dimensions of the segment 54 are not critical so long as it is sufficiently small to be axially reciprocable in the aperture 41' of the housing segment or disk 41 without frictionally engaging the same and be of a sufficiently large diameter to permit abutment thereof by an adjusting spring 60. The disks 55 through 59, however, are critically dimensioned corresponding to the apertures 42' through 46' in the rings 42 through 46 respectively with the piston disks or segments 55, 57 and 59 which are the central and extremity segments having identical outside diameters smaller than the inside diameters of the disks 42, 44 and 46 and having axial dimensions which are substantially identical to each other but greater than the axial dimensions of the disks 42 through 46, which latter disks have substantially identical dimensions to each other. The disks 56 and 58, however, have identical outside diameters substantially larger than the outside diameters of the disks 55, 57 and 59 but substantially smaller than the inside diameters of the disks 43 and 45, and have axial dimensions which are substantially smaller than the axial dimensions of the disks 55, 57 and 59 while being dimensioned identically with each other. The arrangement of the disks 55 through 59 is thus such that alternate disks are substantially dimensioned while adjacent disks are differently dimensioned and the spacing of the disks 56 and 58 is such that while they are in interfacial engagement with the disks 55, 57 and 59, they are also identically spaced between the radial faces of the disks 42 and 44, and the disks 44 and 46 respectively. That is, the disks 56 and 58 are so spaced that the spacing between the disks 42 and 56 is identical to the spacing between the disks 44 and 58; and the spacing between the disks 56 and 44 is identical to the spacing between the disks 58 and 46. With this arrangement of the disk segments, any axial displacement of the piston assembly will result in identical variations in the spacings of the housing disks 45 and piston disks and, at all times, the spacing at one end of each of the piston disks will be identical and spacing of the other side of the piston disks to the housing disks will be identical. This operational characteristic of the piston disks and cylinder disks permits a proper control of fluid flow within the valve between the diaphragms 50 and 51. That is, this characteristic of actuated operation of the piston assembly permits proper fluid flow control through the ports 27', 23', 26', 24' and 28' which correspond in placement to the fluid tubes 23 and 24 leading to the double acting piston cylinder assembly in Figure 1, the fluid flow tubes 27 and 28 leading to the reservoir, and the fluid tube 26 leading to the valve mechanism from a fluid supply pump, respectively. These ports extend axially through the housing 33 and are placed to meet with annular outer peripheral grooves 42a, 43a, 44a, 45a, and 46a in the outer peripheries of the disks 42 through 46 respectively. Radial apertures 27a, 23a, 26a, 24a and 28a are provided in the disks of 42 through 46 to thereby properly communicate the housing ports 27', 23', 26', 24' and 28' respectively with the apertures and space within the cylinder assembly.

By this arrangement of the ports, the cylinder assembly, and the piston assembly, movement or axial displacement of the piston assembly to the left as viewed in Figure 3 will act to close rod end ports 23' from the reservoir port 27' and open the port 23' to the fluid supply port 26', while at the same time acting to close the cap end port 24' from the fluid supply port 26' and open the cap end port 24' to the reservoir port 28' by closing the space between the disks 42 and 56 and the

space between the disks 44 and 58 and at the same time opening the space between disks 56 and 44 and opening the space between the disks 58 and 46. Reverse actuation of the piston 52 will have a reverse effect whereby fluid will be supplied from the port 26' to the port 24' and the port 23' will be exposed to the reservoir port 27'.

To so actuate the piston, the actuator end of the piston rod is provided with a pivot head pivotally connecting the same to an actuator plate 61 carrying a ball pivot socket member 62 and also pivotally engaging the strongly resiliently outwardly urged control button 63 of a micro-switch or the like 64 adjustably positionable by an adjusting screw or the like 65 mounted on the actuator bracket 39. Here it should be noted that the micro-switch 64 and/or similar mechanisms may be provided herein to operate the over travel solenoids and by-pass valves 31 and 32 and that when it is desired to eliminate the micro-switches and the by-pass valves, an over travel spring may be substituted for the micro switch between the actuator plate 61 and the adjusting screw 65. Normally, the resilient bias at the point of engagement of the switch button 63 with the actuator plate 61 is greater than any axial bias on the piston assembly provided by the resilient diaphragms 50 and 51 and the adjusting spring 60 so that any actuating force on the actuator plate 61 applied through the ball pivot socket 62 effects axial movement of the piston assembly for valve actuation. It is only when the limit of movement of the piston assembly to the left is reached that further force on the actuating plate ball pivot socket 62 to the left will cause operation of the micro switch 64 or an over travel spring substituted therefor, or a limit or movement of the lower end of the plate 61 is reached the movement of the piston to the right will operate the micro switch.

The stylus and actuator structure is such that a ball 66 is held between the ball pivot socket 62 on the actuator plate 61 and a ball pivot socket 67 on an inner end of a stylus carrier 68 having a tracer or directional stylus 69 secured in the outer end thereof by set screw or the like 70. The stylus carrier 68 is resiliently mounted in a stylus bushing 71 by a spring 72 seated against a retainer ring 73 in the stylus bushing and urging the stylus carrier into intershoulder engagement, as at 74, with the stylus bushing 71. The stylus bushing 71 is in turn mounted in a ball bearing bushing 75 for substantially frictionless operation and reciprocation therein, the ball bearing bushing being mounted on the actuator bracket 39. The stylus bushing is also urged resiliently against the ball 66 to retain the same between the ball pivot pockets by a small spring 76 on the inner side of the actuating bracket 39.

With this structure, any axial inward force on the stylus 69 will be transferred to the ball 66, to the actuated plate 61 and then to the valve piston assembly, and if the force is of sufficient strength then it will also be transferred to the micro-switch 64 or an over travel spring substituted therefor. If the stylus 69 is freed of engagement then resilient force acting on the piston assembly from the adjusting spring 60 will move the stylus to the right through the force acting through the actuator plate 61 and the ball 66, and if travel is carried beyond the limit of right hand axial movement of the piston 52, then the micro-switch 64, which may be a switch of the double throw type, is actuated oppositely.

This mechanism is also sensitive to radial force applied on the stylus 69 since that will cause relative pivotal movement of the stylus carrier about the shoulder engagement thereof with the stylus bushing at such a point as 74 whereby there will be a result of movement in the actuating plate 61 and thereby in the piston assembly for the valve.

From the foregoing it will be readily deduced that fine adjustment of the valve mechanism is important to smooth operation thereof and for that purpose, the ad-

justor or adjusting mechanism 35 is so coupled to the piston assembly as to provide for very fine adjustment of the resilient force applied on the piston through spring 60 and thereby very fine adjustment of the piston assembly with respect to the cylinder assembly. In this embodiment of the invention the adjusting mechanism 35 includes a differentially threaded internally and externally threaded adjusting screw 77 having its external threads 78 threadably engaging a threaded aperture 79 in the end wall 34 of the housing 33. The outer end of a central aperture 80 in a screw 77 is enlarged to freely receive an inner screw 81 which threadably engages inner threads 82 on the inner end of the screw 77. Further inwardly on the end of the screw 77, the screw 81 has a flanged spring backing member 83 fixed thereon for axial movement therewith, the spring backing member 83 operating to confine the spring 60 of the adjusting mechanism between the end piston disk 54 and the spring backing member 83 itself. By differentially threading the screw 77 so that, for example, the external threads 78 are about 30 threads per inch and the internal threads at 82 are about 32 threads per inch, one revolution or complete turn of the screw 77 by operation of the knurled knob 88 thereon at the outer end thereof will result in an axial movement of the inner screw 81 of about (0.002 inch), the inner screw 81 being fixed against rotational movement by a hexagonal pin 89 fixed therein as at 90 and fixed against rotation while being permitted to move axially by being received in an appropriately configurated hexagonal aperture 91 in the end of the adjusting support bracket 36. Since the screw 81 has an axial movement which is only the difference between the fitting on the two screws, any rough adjustment effected by operation of the knurled knob 88 will result in a fine axial movement of the inner screw 81.

On its innermost end, the screw 81 carries a stop block 100 which is fixed thereon for axial movement therewith by any such means as being slidably engaged on the screw. This stop block is fitted for axial movement within a piston stop 101 which takes the form of a flanged sleeve secured to the end of the piston rod 52 immediately adjacent to the adjusting mechanism or forming a part of the piston disk 54. The exposed end 102 of the flanged sleeve and piston stop 101 is radially inwardly flanged as shown at 103 whereby it cooperates with the stop block 100 in the manner immediately hereinafter described.

In operation of the hydraulic system such as is illustrated in Figure 1 it is highly desirable to meter a fluid flow through the servo valve 25 when the stylus 29 is moving in a direction to seat the contoured edge of the template 30. Also, it is highly desirable to limit movement of the piston rod 52 in the aforesaid direction to thereby eliminate any possible fluttering of the valve spool or piston when the stylus engages the template. To this end, the stop block 100 and flanged portion 103 cooperates to limit movement of the valve spool or piston to such a position that when the valve spool or piston is moved to its maximum limit in a right hand direction as viewed in Figure 3, the piston disks 56 and 58 will be held out of engagement with the immediately adjacent faces of the housing or cylinder disk segment 44 and 46. The adjusting mechanism provides for such a controlled position stop of the piston or valve spool and permits fine adjustment of the stop since fine adjustment of the axial position of the screw 81 will finally adjust the axial position of the stop block 100 and thereby finally adjust the position at which the flanged sleeve or piston stop 101 will engage the stop block 100 and thereby finally adjust the limit of right hand movement of the piston or valve spool 52 as viewed in Figure 3.

From the foregoing it will be readily observed that numerous variations and modifications may be effective without departing from the true spirit and scope of the novel concepts and principles of this invention. I, there-

fore, intend to cover all such modifications and variations as follows within the true spirit and scope of the novel concepts and principles of this invention.

I claim as my invention:

1. In a hydraulic system to control bidirectional actuation, a servo valve comprising a plurality of housing segment plates having respectively different size apertures therein and secured together with the apertures coaxially arranged, the apertures in alternate segment plates being of the same dimensions, a piston resiliently mounted for resilient axial reciprocable movement in the apertures in said segment plates, said piston being comprised of segments of different dimensions corresponding to the apertures in said segment plates and being alternately of the same dimensions, resilient diaphragms sealing the ends of the secured together segment plates and sealingly and resiliently supporting said piston, an actuating plate having pivotal engagement with said piston, radial ports leading from certain of said segment plates, means to control displacement of the piston to control fluid flow between said ports within the valve by controlling pivotal displacement of the actuating plate, and yieldable overtravel means forming a reaction member for said actuating plate.

2. In an hydraulic actuator control valve, a hollow cylinder having regions of differing inside diameters, and fluid ports therein, alternate regions being of substantially the same diameter, a piston reciprocably disposed in said cylinder, said piston having regions of differing outside diameters corresponding to the regions of the cylinder, means sealing said piston and said cylinder and resiliently mounting said piston coaxially within said cylinder for resilient axial displacement, a resilient biasing spring seated against one end of the piston, differential screw means mounted on the cylinder and abutting said spring and carrying stop means to finely adjust metering of the movement of the piston, actuating means coupled to the piston to control axial displacement of the piston and thereby control fluid flow through the ports, and overtravel means forming a reaction member for said actuating means and yielding upon overtravel of said piston.

3. In an hydraulic actuator control valve, a hollow cylinder having regions of differing inside diameters, and fluid ports therein, alternate regions being of substantially the same diameter, a piston reciprocably disposed in said cylinder, said piston having regions of differing outside diameters corresponding to the regions of the cylinder, means sealing said piston and said cylinder and resiliently mounting said piston coaxially within said cylinder for resilient axial displacement, a pivotal actuating plate coupled to the piston, displacement sensing means coupled to the actuating plate to displace the piston upon displacement of the displacement sensing means to control fluid flow through the valve, and overtravel means forming a fulcrum for said actuating plate and yielding upon

overtravel of said piston effected by displacement thereof by said displacement sensing means.

4. In an hydraulic actuator control valve, a hollow cylinder having regions of differing inside diameters, and fluid ports therein, alternate regions being of substantially the same diameter, a piston reciprocably disposed in said cylinder, said piston having regions of differing outside diameters corresponding to the regions of the cylinder, means sealing said piston and said cylinder and resiliently mounting said piston coaxially within said cylinder for resilient axial displacement, means biasing said piston in one axial direction, an actuating plate pivotally coupled to the piston, displacement sensing means pivotally connected to the actuating plate to displace said piston, said last mentioned means including a displacement sensing member, means biasing said member towards said actuating plate, a yieldable fulcrum for said actuating plate compensating for overtravel of said displacement sensing means and pivot means coupling the same to said actuating plate whereby displacement of the sensing means operates to displace the piston and thereby control fluid flow through the valve.

5. In a hydraulic system to control bidirectional actuation, a servo valve comprising a housing having a plurality of abutting housing segment plates within said housing in engagement with the wall thereof and having respectively different size axially extending apertures therein and secured together with the apertures coaxially arranged, the apertures in alternate segment plates being of the same dimensions, a piston resiliently mounted for axial reciprocable movement along the apertures in said housing segment plates, said piston being comprised of segments of different dimensions corresponding to the apertures in said housing segment plates and being alternately of the same dimensions, radial ports in said segment plates, radial ports in said housing in alignment with the ports in said segment plates, actuating means for said piston controlling displacement thereof and thereby controlling fluid flow within the valve between said ports, and over travel means engaging said actuating means and yielding upon over travel of said piston and forming a reaction member for said actuating means.
